UNITED STATES PATENT OFFICE.

FREDERICK W. COLLIER, OF WORCESTER, MASSACHUSETTS, ASSIGNOR TO PACKMORE MANUFACTURING COMPANY, OF WASHINGTON, DISTRICT OF COLUMBIA, A CORPORATION OF DELAWARE.

BRUSH-ADJUSTING MEANS FOR CLEANING-MACHINES.

1,313,261.

Specification of Letters Patent.

Patented Aug. 19, 1919.

Application filed August 22, 1914, Serial No. 858,093. Renewed January 15, 1919. Serial No. 271,336.

To all whom it may concern:

Be it known that I, FREDERICK W. COLLIER, a citizen of the United States, residing at the city of Worcester, county of Worcester, 5 and State of Massachusetts, have invented a new and useful Improvement in Brush-Adjusting Means for Cleaning-Machines, of which the following is a specification.

My invention relates to improvements in brush adjusting means for cleaning machines, and the object of my improvements is to construct a novel means for raising and lowering the brush of a combined sweeper and vacuum cleaning machine in 10 order first to raise the brush into and out of contact with the surface so that the machine may be employed either as a sweeper, a vacuum cleaner, or a combined sweeper and vacuum cleaner; and, second, to provide 15 adjustment to compensate for wear on the bristles as well as to provide for different lengths of carpet nap.

With the above purposes in view my invention consists in certain novel features 20 of construction and arrangement of parts as will be hereinafter more fully described, pointed out in the claims and illustrated in the accompanying drawings, in which:

Figure 1 shows in elevation a combined 25 vacuum and sweeper cleaning machine, having the device of my invention applied thereto.

Fig. 2 is a rear elevation of the machine showing the brush-carrying yoke in its lowered position in solid lines, and elevated in dotted lines.

Fig. 3 is a detail elevation showing the rear face of the yoke-adjusting means.

Fig. 4 is a detailed sectional elevation 40 taken on the line 4-4 of Fig. 2.

Fig. 5 is a detailed sectional elevation taken on the line 5-5 of Fig. 2.

Fig. 6 is a plan of the yoke detached from the machine; and,

Fig. 7 is a detailed sectional plan showing the construction of supporting wheel held to its shaft by the brush-adjusting yoke.

Referring by numerals to the accompanying drawings:

7 designates the casing of the machine, 8 the operating handle therefor, 9 the drive wheels associated with the suction-creating means and which support the rear end of the machine, and 10 the driving wheels which

operate the sweeper brush of the machine 55 and which wheels support the forward end of the machine.

Pivottally connected with the casing 7, to its side walls in advance of the wheels 10 are the arms 11—11 forming part of a yoke, 60 the rear body portion 12 of which extends around the rear end of the casing, the side arms 11 being extended outwardly beyond the wheels 9 and 10. Formed in said rear body portion of the yoke are the vertically 65 disposed slots 13, and carried by the casing registering with said slots are the screw seats 14.

15 designates a plate having at its upper and lower margins the ribs 16 which overlap the margins of the rear body portion 12 of the yoke. Formed in said plate, registering with said vertical slots are the diagonal slots 17. Extending through the diagonal slots 17 in the plate 15, through the vertical 70 slots 13 in the rear portion of the yoke and seated into the screw seats 14, carried by the casing, are the screws 18.

Formed in the plate 15, between the diagonal slots 17, is a circular opening 19 into 75 which there is fitted a disk 20 having the peripheral flanges 21 which ride over the margins of the opening 19. This disk 20 is secured to the body portion 12 of the yoke by means of a pivot 22 arranged eccentrically to the disk 20 and arranged to move in a slot 23 formed in the yoke.

For rotating the disk 20, I attach thereto the handle 24 the free end thereof being turned outwardly slightly to facilitate 80 grasping.

Carried by the arms 11 of the yoke, between the driving wheels 9 and 10 of the machine, are bearings 25 in which is rotatably mounted the brush 26 having at its 85 ends the rollers 27 which are held in contact with the wheels 10 for the operation of the brush. The body portion of the brush rides in the openings 28 of the machine casing so that the brush may be raised and lowered, as desired.

In Figs. 1 and 2 I show in solid lines the yoke in its lowered position, and in dotted lines the yoke in its elevated position, in which latter position the brush is carried out 100 of contact with the surface to be cleaned. When the parts are adjusted to the position indicated in dotted lines in Fig. 2 the plate

15 is bodily moved upon the yoke causing the inclined edges of the slots 17 therein to engage with the studs or pins 18 which are stationarily supported relative to the casing. 5 The slotted plate thus acts as a double-faced inclined plane and forces the yoke in one direction or the other, accordingly as the plate is laterally moved. The eccentric 10 19 and the handle by which it is turned constitute means for conveniently manipulating the plate 15. By reason of the eccentric arrangement the disk will be held by friction in any desired position between its limits of movement, so that the yoke may be held 15 in any desired elevation to accommodate different lengths of nap of carpet, as well as to hold the brush in any desired degree of contact with the surface to be cleaned. It is to be observed that the yoke also serves the 20 function of retaining the wheels upon their respective carrying-shafts, without the employment of any extraneous securing devices for said wheels.

I claim:

- 25 1. The combination, in a carpet cleaning machine, with a casing, and a yoke pivoted thereto carrying a brush for acting upon the carpet, of an inclined plane device supported upon the yoke and movable laterally relatively thereto, and a bearing against which the said inclined plane device acts, arranged for adjusting the yoke and the brush it carries vertically as the inclined plane device is moved laterally.
- 30 2. The combination, in a carpet cleaning machine, with a casing, a yoke pivoted thereto, a brush supported in the yoke, and means for driving the brush, of an inclined plane

device carried by the yoke and shiftable laterally relatively thereto, and stationary 40 projections carried by the casing with which the said inclined plane device engages, whereby shifting of it causes vertical movement of the yoke and the brush it carries.

3. The combination, in a carpet cleaning 45 machine, with a casing, a yoke pivoted thereto, a rotatable brush carried by the yoke, and means for driving the brush, of a plate in which is an inclined slot, carried by the yoke and shiftable relatively thereto, and a 50 projection carried by the casing and extending into the slot of the plate, the engagement of the plate as it is shifted with the said projection causing vertical movement of the yoke. 55

4. The combination, in a carpet cleaning machine, with a yoke pivoted thereto and having arms at the sides of the casing and a cross-piece extending past one end, a rotatable brush carried by the yoke, and means 60 for driving the brush, of a plate mounted upon the cross-piece of the yoke, the plate having formed in it inclined slots, and the cross-piece having formed in it vertical slots that register with the inclined slots in the 65 plate, pins carried by the casing extending through the said slots, and an eccentric for shifting the plate relative to the cross-piece, substantially as set forth.

In witness whereof, I have signed this 70 specification in the presence of two subscribing witnesses.

FREDERICK W. COLLIER.
